UNITED STATES PATENT OFFICE.

JAMES JOHNSON, OF HACKETT, PENNSYLVANIA.

WIRE-STRETCHER.

No. 902,968.

Specification of Letters Patent.

Patented Nov. 3, 1908.

Application filed January 21, 1908. Serial No. 411,881.

To all whom it may concern:

Be it known that I, JAMES JOHNSON, a citizen of the United States of America, residing at Hackett, in the county of Washington and State of Pennsylvania, have invented certain new and useful Improvements in Wire-Stretchers, of which the following is a specification, reference being had therein to the accompanying drawing.

10 This invention relates to a wire stretcher, and the object of my invention is to provide a simple and inexpensive device for easily and quickly stretching a wire.

15 My invention aims to provide a device wherein positive and reliable means are employed for stretching a wire or drawing the ends of two pieces of wire together whereby a splice can be easily and quickly made. In this connection my device is intended for 20 stretching the wires of a wire fence, trolley wires, guide wires, and such wires that are stretched before they are placed in use. To this end, I have devised a hook-shaped rack adapted to be connected to one end of a wire. 25 The rack is movably mounted in a suitable housing wherein a combined pinion and ratchet wheel is located and adapted to be operated by a lever to move the rack. The housing is connected to the opposite end of 30 the wire or to the end of another wire as the case may demand.

35 The detail construction entering into my invention will be presently described and then specifically pointed out in the appended claim.

Referring to the drawings: Figure 1 is an elevation of my wire stretching device, Fig. 2 is a longitudinal sectional view of the same, partly in elevation, Fig. 3 is a cross 40 sectional view of the device taken on the line $x-x$ of Fig. 2, Fig. 4 is a perspective view of a housing forming a part of this device, and Fig. 5 is a perspective view of a portion of a channel-shaped rack used in connection 45 with the device.

To put my invention into practice, I construct my wire stretching device of an inverted channel-shaped housing 1 having depending pierced lugs 2 in which is mounted 50 a shaft 3. Upon the shaft within the housing 1 is journaled a toothed wheel, serving functionally as a pinion or ratchet wheel. Loosely mounted upon the outer ends of the shaft 3 is a bifurcated end 5 of an operating 55 lever 6. In the bifurcated end 5 of the operating lever 6 is pivotally mounted a pawl

7 normally held in engagement with the toothed wheel 4 by a spring 8.

Slidably mounted in the housing 1 above the toothed wheel 4 is a channel-shaped rack 60 9, meshing with said toothed wheel, and having a hook-shaped end 10 adapted to be connected to the end of a wire 11. In the housing 1 is pivotally mounted a spring pressed dog 12 adapted to engage the toothed wheel 65 4, and a hook 13 adapted to be connected to the end of a wire 14. After the hooks 10 and 13 have been connected to the ends of the wires 11 and 14 respectively, it is only necessary to oscillate the operating lever 6 70 to impart movement to the toothed wheel 4 and cause the rack to be moved in the housing 1, to bring the ends of the wires 4 and 14 in close proximity to one another. The spring pressed dog 12 prevents a rearward movement of the toothed wheel 4, after it has been moved in one direction by the operating lever 6.

It will thus be observed that I have devised a novel ratchet mechanism, which 80 serves functionally for moving the rack, and as to the manner of securing the wires 14 and 11 together, I do not care to confine myself in this particular.

The wire stretching device in its entirety 85 is constructed of strong and durable metal, and I reserve the right to make such structural changes as are permissible by the appended claim.

Having now described my invention what 90 I claim as new, is:—

A wire stretcher comprising an inverted U-shaped housing having one end cut away, and its open side provided with apertured offsets near said cut away end, a shaft mounted in said offsets and of greater length than the width of the housing whereby said shaft projects from each of the offsets, a toothed wheel connected to said shaft and positioned between the vertical walls of the housing, 100 a bifurcated lever loosely mounted on the ends of said shaft and straddling said housing, a pawl mounted within said lever near one end of the bifurcation and adapted to engage said toothed wheel when the lever is 105 oscillated thereby intermittently rotating the wheel, a coil spring arranged within the bifurcation and connected at one end to the lever and at its other end to said pawl, a channel shaped bar slidably mounted in said 110 housing against the closed side wall thereof and having its lower face provided with

teeth adapted to be engaged by said toothed wheel whereby the bar is shifted when the wheel is actuated, one end of said bar provided with a hook adapted to connect the wire, a dog pivotally mounted within and projecting from said housing and engaging said toothed wheel to prevent back rotation thereof, a coil spring arranged within the housing and having one end connected to the housing and its other end to said dog

and a hook having its shank secured between the vertical walls of the housing and adapted to engage the end of another wire, substantially as described.

In testimony whereof I affix my signature 15 in the presence of two witnesses.

JAMES JOHNSON.
